UNITED STATES PATENT OFFICE

JOHN M. CHRISTMAN, OF DETROIT, MICHIGAN, ASSIGNOR TO PACKARD MOTOR CAR COMPANY, OF DETROIT, MICHIGAN, A CORPORATION OF MICHIGAN

CRIMPING MACHINE

Application filed November 25, 1927. Serial No. 235,481.

This invention relates to crimping machines and more particularly to machines for crimping retaining members onto the ends of coil springs.

5 An object of the invention is to provide a machine for rolling cylindrical members to reduce the diameter thereof.

Another object of the invention is to provide a machine for crimping flanges on cylindrical members having grooves for the reception of the end coils of helical springs, to partly close the grooves and thereby retain the coils therein.

Another object of the invention is to provide a crimping machine having work supporting devices and a rotatable member and a fixed member coacting therewith to effectively crimp or peen the work pieces carried on the support devices.

20 Another object of the invention is to provide a crimping machine comprising a rotatable crimping member and fixed crimping members positioned eccentrically thereto so that the cooperating faces of the crimping members will provide an arcuate slot gradually decreasing in cross section.

Yet another object of the invention is to provide a crimping machine comprising a rotatable working head having thereon a plurality of work supporting devices adapted to support work pieces to be operated upon by a rotatable crimping member cooperating with fixed crimping members positioned eccentrically thereto and provided with yielding means whereby pressure between the crimping members can be maintained at a predetermined value.

A further object of the invention is to provide a crimping machine of unique and compact structure wherein a rotatable member is operated through a suitable source of motive power to coact with a plurality of arcuate members arranged to provide an arc of considerable length eccentrically adjusted to the rotatable member, with one or more of the arcuate members yieldably supported and a rotatable work supporting head carrying a plurality of work supporting devices positioned intermediate the rotatable member and the arcuate members.

A still further feature of my invention is to provide a crimping machine which has the advantages of a positive action, is highly efficient in operation and yet of marked simplicity as a whole in respect to each of its component parts so that its manufacture is economically facilitated, both with regard to parts and their assembly.

Other objects of the invention will appear from the following description taken in connection with the drawings which form a part of this specification and in which:

Fig. 1 is a front elevation,

Fig. 2 is a vertical sectional view taken substantially on line 2—2, Fig. 1, and

Fig. 3 is a longitudinal sectional view of a double coil spring and the retaining members therefor.

Referring by numerals to the drawings, 10 represents a base plate supported in any suitable manner such as by a pedestal or, as shown, by a plurality of legs 11. Bolted or otherwise secured upon the base is a frame 12 having bearing portions 13 and 14. A housing 15 is arranged intermediate the bearing portions 13 and 14 and a radial flange 16 is formed integral with the bearing portion 13. This flange is provided with an arcuate rim 17 formed normal thereto and of sufficient width to provide a deep recess 18. The bearing portions are bored as indicated at 19 and 20, the bores being in axial alignment with respect to each other and with respect to the arcuate rim 17. The bore 19 is somewhat larger than the bore 20 and is fitted with a sleeve or collar 21, the inner diameter of which is equal to the diameter of the bore 20. This sleeve is provided with a radial flange 22 bolted to the bearing portion 13 to retain the sleeve in the bore 19 in a fixed position with one end thereof projecting through the recess 18 to a position substantially parallel with the face of the rim 17, the object of which will hereinafter appear.

The bore 20 and the sleeve 21 are fitted with suitable bearings 24 in which is journaled a shaft 25 having keyed thereupon within the housing 15 a worm gear 26 in mesh with a worm gear 27 on a shaft 28

suitably journaled as indicated at 29 and provided with a pulley 30. The pulley 30 is adapted to be driven by any suitable source of motive power or, as shown, by a belt 31 connecting the pulley 30 to a pulley 32 driven by a motor 33 supported on a bracket 34 mounted beneath the base plate.

Any suitable clutch for disengaging the drive may be employed or the machine may be controlled through the motor. The sleeve 21 has rotatably mounted thereupon a work supporting head 35 secured against axial movement by the flange 22 and the plate 36 pinned or otherwise secured on the end of the sleeve. This work supporting head is positioned within the recess 18 and is in the form of a disk having an enlarged rim 37 formed with radial lugs 38 arranged in pairs and equally spaced as shown in Fig. 1. An arm 39 is pivoted as at 40 between each pair of lugs 38 and is limited in its movement by a transverse pin 41 in the lugs engaging a slot 42 in the arm. The free ends of the arms have formed integral therewith and normal thereto sleeves 43 in which are mounted work holding devices to be hereinafter described.

The shaft 25 has a reduced end 44 threaded to receive a nut 45. A disk 46 is keyed upon the reduced end portion of the shaft and further secured in position by the nut 45. This disk is provided with an annular shouldered portion 47 on which is secured by bolts 48 an annular member 49 of hardened steel constituting a rotatable crimping member adaptable for cooperation with a series of fixed crimping members 50.

The crimping members 50 are mounted upon the face of the rim 17 in the same plane with a rotatable crimping member 49. As shown, each crimping member 50 comprises a plate of hardened steel having an arcuate edge 51 and an oppositely disposed polygonal edge 52. The plate is further provided with a plurality of slots 53 adapted to receive stud bolts 54 threaded in the face of the rim 17. The arcuate edge 51 is positioned opposite the peripheral face of the annular member 49 and is made adjustable thereto by means of the slots 53 and stud bolts 54 and the plate is secured in adjusted position by set bolts 55 engaging the polygonal edge 52, the set bolts being mounted in brackets or arms 56 formed upon the rim 17.

The crimping members 50 are arranged end to end to provide an arc of considerable length which is adjusted eccentrically to the periphery of the annular rotatable crimping member providing between the arcuate edges 51 of the fixed crimping members 50 and the peripheral face of the annular member 49 an arcuate groove or channel 57 which gradually diminishes in width from one end to the other. The last member in the series

or group of crimping members 50 is yieldably held in position by coil spring 58 mounted upon bolts 59 threaded into the rim 17 and bearing upon the polygonal edge 52 with blocks 60 interposed, the object of which will hereinafter appear.

Mounted alternately in the sleeves 43 on the free ends of the arm 39 is a bushing 61 having mounted therein a spindle 62 with a reduced end portion 63, and a sleeve in two sections 64 and 65, both of which are secured in the sleeve 43 in a fixed position. The sleeve 64 has a partition 66 apertured to receive and to provide a guide for a spindle 67 and to serve as an abutment for one end of a coil spring 68 wound upon the spindle with its other end bearing against a pin 69 positioned transversely in the spindle. This spindle is further supported and guided by a bushing 70 secured in the sleeve section 65. One end of the spindle 67 is provided with a pin 71 passing through the diameter thereof and suitably secured in position and a reduced end portion 72. The other end of the spindle is reduced and fitted with washers 73 between which is mounted a ball bearing disk 74 adaptable for engagement with a stop 75 arranged on the frame. The spindles 62 and 67 project through and beyond the slot 57.

The assembled spring unit comprises two sections of helical coils 76 and 77 of substantially the same diameter arranged coaxially between retainers 7 and 79, one of which, the retainer 78, has a diametral slot 80 adapted for the reception of a key and an inturned shoulder with an integral sleeve or collar 81. The retainers 78 and 79 are cylindrical members, each having on its periphery a double spiral groove 82 adapted to receive the respective end coils of the spring sections and to retain the same in their proper angular position. Intermediate the double spiral grooves are formed marginal lips or edges 83 adaptable to be peened or rolled tightly against the coils in the grooves to retain the springs in proper relation with respect to each other and with respect to the retaining members.

In operation, the spring unit is placed first one end and then the other upon the work carrying devices according to the end to be crimped. When it is desired to crimp the retaining end 79, this member is slipped upon the spindle 62 and advanced until the reduced end portion 63 on the spindle engages the sleeve 81 on the retaining member 78 and when it is desired to crimp the retaining member 78, this member is slipped on the spindle 67, the reduced end portion 72 on the spindle engaging the sleeve 81 with the pin 71 in the spindle engaging the diametral slot in the retaining member 78.

Assuming that power has been applied to the machine and that the spring units have been placed upon the spindles 62 and 67 as

hereinabove described, the disk 46 carrying the annular crimping member 49 is mounted upon and rotated by the shaft 25 driven by a worm gear 26 which in turn is driven by a worm gear 27 on the shaft 28 connected to the source of motive power. With the disk 46 rotating slowly, making approximately one revolution per minute, the work supporting head is rotated to advance the spring units upon the spindles 62 and 67 into the receiving end of the slot 57 where the retaining members 78 and 79 are caught between the annular rotatable crimping member 49 and the stationary or fixed crimping members 50. The work supporting head carrying the spindles 62 and 67 has no positive drive but is rotated slowly by a drag on the spindles exerted by the work mounted thereon engaging the crimping members 49 and 50, constituting, as it were, a clutch between these elements.

The slot 57 has a gradual taper from its receiving end to its discharge end, the taper being formed by the eccentric position of the member 49 to the arcuate faces of the members 50. As the retaining members 78 and 79 enter the slot 57 they are caused to revolve by the rotation of the annular rotatable crimping member and in the rotation of these members they travel through the slot 57 and are gradually pressed between the faces of the stationary or fixed crimping members 50 and the periphery of the annular crimping member 49 and in the course of travel the pressure on the retaining members becomes greater and serves to peen or roll the lips or edges 83 against the end coils of the springs 76 and 77 with sufficient pressure to secure the coils in the retainers in their proper relation. In order that the pressure between the crimping members will not be too great and to allow for slight variances the last one or more of the fixed crimping members 50 is yieldably mounted, and to provide for the ready removal of the spring units from the spindle 67, this spindle is provided with a kick-off device adapted to engage a stop immediately upon the spindle passing through the discharge end of the slot. As the spindles pass through the discharge end of the slot the arms 39 through the weight of the sleeves upon the free ends thereof and the spindles supported therein drop sufficiently to disengage the retaining members from the periphery of the annular crimping members, the drop being limited. In this position the spring units may be readily removed or placed upon the spindles for operation therupon. Although this invention has been described in connection with certain specific embodiments, the principles involved are susceptible of numerous other applications that will readily occur to persons skilled in the art. The invention is therefore to be limited only

as indicated by the scope of the appended claims.

Having thus described the various features of my invention, what I claim as new and desire to procure by Letters Patent is:

1. A crimping machine comprising a rotatable member, an arcuate member positioned eccentrically thereto, a work supporting head and work supporting devices on the head for rotatably supporting work pieces intermediate the rotatable member and the arcuate member.

2. A crimping machine comprising an annular rotatable member, an arcuate member positioned eccentrically thereto, a work supporting head and work holding devices on the work supporting head intermediate the rotatable member and the arcuate member.

3. A crimping machine comprising an annular rotatable member, means for driving the rotatable member, an arcuate member positioned eccentrically to the rotatable member, a work supporting head mounted for rotation on the same axis with the rotatable member and work holding devices carried by said work supporting head and extending between said rotatable member and arcuate member.

4. A crimping machine comprising an annular rotatable member, means for driving the rotatable member, an arcuate member positioned eccentrically to the rotatable member, means for yieldably retaining the arcuate member in position, a work supporting head and work holding devices carried by the head between the rotatable member and the arcuate member.

5. A crimping machine comprising an annular rotatable member, means for driving the rotatable member, an arcuate member positioned eccentrically to the rotatable member, a work supporting head mounted for rotation adjacent to the rotatable member and work holding devices arranged in spaced relation on the work supporting head and extending between the rotatable member and the arcuate member.

6. A crimping machine comprising an annular rotatable member, means for driving the rotatable member, an arcuate member yieldingly supported eccentrically to the rotatable member and a rotatable work supporting head for supporting work pieces between the rotatable member and the arcuate member.

7. A crimping machine comprising an annular rotatable member, means for driving the rotatable member, an arcuate member yieldingly supported eccentrically to the rotatable member, a work supporting head journaled for rotation on the same axis with the rotatable member, work holding devices pivoted on the work supporting head and extending between the rotatable member and the arcuate member.

8. A crimping machine comprising an annular rotatable member, means for driving the rotatable member, a plurality of arcuate members positioned eccentrically to the rotatable member, one or more of the arcuate members yieldingly secured in position, a work supporting head and means carried by the head for supporting work pieces between the rotatable member and the arcuate member. 70
9. A crimping machine comprising an annular rotatable member and means for driving the same, arcuate members supported eccentrically to the rotatable member and means for adjusting the arcuate members radially, one or more of the arcuate members being yieldingly supported, a work supporting head mounted for rotation on the same axis with and adjacent to the rotatable member and work holding devices mounted on the work supporting head for oscillatory movement between the rotatable member and the arcuate members. 75
10. A crimping machine comprising an annular rotatable member, an arcuate member mounted eccentrically thereto for cooperation therewith, a work supporting head mounted for rotation adjacent to the rotatable member, and a plurality of work holding devices pivoted upon the work supporting head for oscillatory movement between the rotatable member and the member mounted eccentrically thereto. 80
11. A crimping machine comprising a frame, a shaft mounted thereon, an annular member carried by the shaft, an arcuate member supported by the frame eccentrically with respect to the rotatable member, a work supporting head journaled upon the frame for rotation independent of the shaft, a plurality of work holding devices on the work supporting head mounted for oscillatory and rotatable movement between the rotatable member and the arcuate member. 85
12. A crimping machine comprising a frame, a sleeve mounted on the frame, a shaft in the sleeve, an annular member carried by the shaft, a ring upon the annular member, an arcuate member supported on the frame eccentrically to the ring, a work supporting head journaled upon the sleeve, work holding devices pivoted upon the head for oscillatory and rotatable movement between the annular member and the arcuate member. 90
13. A crimping machine comprising a frame having an arcuate flange, a sleeve on the frame concentric to the arcuate flange, a shaft journaled in the sleeve, an annular member keyed on the shaft, a ring carried by the annular member, a plurality of arcuate members on the flange, one or more of the arcuate members being yieldingly supported, a work supporting head journaled upon the sleeve adjacent to the annular member 100
14. In a crimping machine, the combination of an arcuate member, an annular rotatable member mounted eccentrically thereto and adapted for cooperation therewith, a work supporting head having work holding devices mounted thereupon and projecting between the arcuate member and the rotatable member and means for ejecting work pieces from the work holding devices. 105
15. In a crimping machine, the combination of a fixed arcuate member, an annular rotatable member journaled eccentrically thereto in spaced relation to provide an arcuate converging slot, a work supporting head rotatably mounted adjacent to the annular rotating member, spindles carried by the work supporting head for supporting work pieces in the slot and means for rotating the annular member. 110
16. In a crimping machine, the combination of a fixed arcuate crimping member and an annular rotating crimping member mounted eccentrically thereto and in spaced relation, a work supporting head having work holding devices thereon projecting between the arcuate crimping member and the annular rotatable crimping member and a trip means for ejecting work pieces from the work holding devices. 115
17. In a crimping machine, a work supporting head comprising an annular member mounted for rotation, arms pivoted upon the periphery of the annular member, means for limiting the movement of the arms, means upon the free end of the arms for supporting a work piece and means for ejecting the work piece from the support. 120
18. In a crimping machine, a work supporting head comprising a hub portion, a web portion and a rim portion, a plurality of lugs upon the rim arranged in pairs in spaced relation, arms pivoted between each pair of lugs, means for limiting the movement of the arms, work holding devices upon the ends of the arms and means for ejecting work pieces from the arms. 125
19. A crimping machine comprising an annular rotatable member having a peripheral flange provided with lugs arranged in pairs in spaced relation, arms pivoted between the lugs, means for limiting the movement of the arms, sleeves upon the free end of the arms, work holding devices supported in the sleeves and means for actuating the work holding devices for ejecting work pieces supported thereon. 130
20. A method for securing helical springs to retaining members comprising crimping the retaining members upon the end coils of the spring by rolling the spring and re- 135

taining member through a converging slot.

21. A method for securing helical springs to retaining members comprising passing an assembled spring and retaining member through a converging arcuate slot whereby the retaining member is deformed for clamping the end coils of the spring.

10 22. A method for securing helical springs to retaining members comprising assembling a spring and retaining member and rotating the assembly through a converging arcuate slot and rotating one of the side walls of the slot whereby the retaining members are deformed to clamp the end coils of the spring.

15 23. A method for securing double helical springs to cylindrical retaining members having spiral grooves for the reception of the end coils of the springs, by assembling the springs and retaining members and rotating 20 the assembly through a converging arcuate slot, for deforming the retaining members to clamp the springs in the grooves therein.

25 24. A method of securing coil springs to retaining members which comprises screwing the end turns of the spring into the retaining member, and crimping said member on said end turns.

In testimony whereof I affix my signature.
JOHN M. CHRISTMAN.
